Primary Examiner — Catherine Ho*Assistant Examiner* — Natalya M Rapundalo(57) **CLAIM**

The ornamental design for a sealed tank, as shown and described.

DESCRIPTION

FIG. 1 is a front perspective view of a sealed tank showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a sectional view taken along line **8-8** of FIG. 6. The broken lines depict portions of the sealed tank that form no part of the claimed design.
